UNITED STATES PATENT OFFICE.

WILLIAM WHITEHEAD RICHARDSON, OF LONDON, ENGLAND.

MINERAL CLASSIFYING AND CONCENTRATING APPARATUS.

Application filed September 25, 1920. Serial No. 412,798.

To all whom it may concern:

Be it known that I, WILLIAM WHITEHEAD RICHARDSON, subject of the King of Great Britain and Ireland, residing at 4 London

5 Wall Buildings, London, in the county of London, England, have invented certain new and useful Improvements in Mineral Classifying and Concentrating Apparatus, of which the following is a specification.

10 My invention relates to an improved arrangement and construction of rotating trommel for mineral classifying and concentrating apparatus.

In order to obtain effective extraction of mineral values and at the same time maintain a useful capacity by means of a rotating cylinder lined with grooved plates, I have invented the apparatus in form as is hereinafter described.

20 According to the present invention I employ a special arrangement and construction of trommel comprising a series of short cylinders or drums connected together end to end. These short cylinders or drums are of

25 two sizes which alternate so that the trommel comprises a series of cylinders or drums in which there is first a large and then a small and then a large cylinder or drum, a small cylinder or drum alternating between

30 each pair of large cylinders or drums. Either the large or the small cylinders are arranged concentric with each other upon the same axis about which the trommel as a whole is adapted to be rotated, whilst the

35 intermediate cylinders or drums are arranged eccentric to the alternate concentric cylinders and these eccentric cylinders are so arranged that their centres are spaced around the axis of the concentric cylinders,

40 so that each successive eccentric cylinder is slightly in advance of or behind the adjacent eccentric cylinder.

When the trommel is rotated about the axis of the concentric cylinders the eccentric cylinders will travel an eccentric path whilst rotating, and the pitch of the centres of these eccentric cylinders is such that a line connecting their centres will form a helical path round the axis of the eccentric cylinders.

45 A convenient arrangement of these eccentric cylinders is to set the centre of each one 90° in advance or behind the centre of the adjacent eccentric cylinder.

A complete trommel may be made up of

any number of such alternate concentric and 55 eccentric cylinders arranged as described and if desired these short cylinders or drums may increase or decrease progressively in diameter from end to end of the trommel, or they may be made to vary in batches or 60 blocks, a suitable number of short cylinders or drums of equal dimensions being connected to another batch or block of such drums of a larger or smaller dimension and other such blocks of cylinders or drums being connected end to end so as to form the 65 whole trommel.

Instead of employing eccentric drums or cylinders between the concentric drums, I may employ a series of eccentric divisions 70 or walls arranged in a cylinder or cylinders so as to form a number of compartments separated by eccentric divisions, which eccentric divisions may be spaced in advance of or behind each other as already described 75 in connection with the eccentric drums.

The cylinders or drums which are connected end to end in any suitable manner to form the complete trommel, are formed from or lined with riffle plates bent to a cylindrical formation. These riffle plates are provided with a series of shallow grooves running circumferentially round the interior of the riffle plates and small pockets or recesses are formed at intervals in the base of these 80 circumferential grooves for the retention of the values to be separated from the material treated. These pockets are arranged in the bottom of the grooves and are provided with substantially square or upright walls at their 85 ends so as to receive and retain the values extracted from the material.

In a modification these pockets may be provided with a substantially square or upstanding wall at one end and an inclined 90 lead in at the other end, which inclined face is arranged at the front of the pocket in reference to the direction of travel. The various short cylinders or drums which form the trommel may be flanged and connected together in any suitable manner or other means may be employed for building up the trommel in the form described.

100 In order that the invention may be more readily understood reference is made to the 105 accompanying sheet of illustrative drawings in which:—

Fig. 1 is a longitudinal section of a portion of a trommel constructed according to

one arrangement of my invention supported so as to rotate upon rollers.

Fig. 2 is an end view thereof.

Fig. 3 is a plan of a portion of one of the riffle plates from which the short drums are built up.

Figs. 4 and 5 are respectively cross section and end section on the lines A—B and C—D of Fig. 3, and

10 Fig. 6 shows a modified form of pocket. Referring to Figs. 1 and 2 the trommel 1 is built up of a series of short cylinders or drums, comprising large drums 2 and smaller drums 3, the smaller drums 3 being arranged 15 between successive pairs of the larger drums 2 so that the drums 2 and 3 alternate. The larger drums 2 are here shown arranged concentric with each other upon the same axis whilst the intermediate drums 3 are 20 arranged eccentric with the larger drums 2 and each of the succeeding smaller eccentric drums 3 are spaced 90° in advance of the previous smaller drum 3 so that the centre of each eccentric drum is progressively 25 spaced 90° in advance of the previous one.

Fig. 2 shows the eccentric drums 3 spaced at 90° apart and having their centres successively situated at 4, 5, 6 and 7 and the corresponding outlines of each of the eccentric drums 3 are shown in full lines, dotted lines, dot and dash lines and double dot and dash lines. The adjacent drums 2 and 3 are flanged at 8 and connected together in any suitable manner end to end as shown in 35 Fig. 1.

The trommel is shown mounted so as to rotate upon rollers 1^a upon horizontal shafts supported in a frame. These shafts may be driven by belts from a suitable motor.

40 Referring now to Figs. 3, 4 and 5, each of the drums 2 and 3 is formed from riffle plates 9 having a series of longitudinal grooves 10 therein. These plates 9 are bent or otherwise suitably formed to the shape of a short cylindrical drum so that the grooves 10 run circumferentially around the interior of the drums 2 or 3.

These grooves 10 are formed with slightly rounded edges 11 leading into the grooves, 50 and recesses or pockets 12 are provided at intervals in the base of each groove 10. These pockets 12 are pressed out or otherwise formed in the base of each groove 10 so as to have substantially square or upright ends 13.

In Fig. 6 is shown a modified form of pocket 14 having one upstanding or substantially vertical end 15 and an inclined end 16 which is intended to lead in the direction 60 of rotation.

In so far as capacity is concerned this form of construction will allow cylindrical sections which will give the best average proportions, and the grade to promote continuous and rapid flow is produced by the 65

eccentric position of the smaller diameters to the larger diameters, whereby each smaller section, once in each revolution, raises its load which by action of the water is washed off into the lower channel formed 70 by the following larger section, and in this way it may be said that a spiral path is formed which causes the solids to travel outwards.

The extraction of values is greatly accelerated through separation due to the periodical immersion of the solids which are inclined to gather and ride dry on the rising side of the cylinder, and this is effected as each pair of small and large sections are at 80 the extreme difference of centres when the vertical position is reached.

These values which are separated from the dirt seek the bottom and find their way first into the grooves and subsequently into the 85 small pockets in the bottom of the grooves, and the values are further prevented from being washed outward by the protection of the channels formed by the difference in diameters of the cylindrical sections. 90

I claim:—

1. In mineral classifying and concentrating apparatus, a rotatable trommel comprising a series of cylindrical spaced drums arranged concentrically to a common axis, and a series of cylindrical drums arranged alternately between the drums of the first mentioned series and each successively angularly displaced eccentrically of said common axis, the drums of the first series being of 100 different diameter to the drums of the second series.

2. In mineral classifying and concentrating apparatus, a rotatable trommel comprising a series of cylindrical spaced drums arranged concentrically to a common axis, a series of cylindrical drums arranged alternately between the drums of the first mentioned series and each successively angularly displaced eccentrically of said common axis, and riffle plates forming the interior wall of 105 each of said drums, and having circumferential grooves.

3. In mineral classifying and concentrating apparatus, a rotatable trommel comprising a series of cylindrical spaced drums arranged concentrically to a common axis, a series of cylindrical drums arranged alternately between the drums of the first mentioned series and riffle plates forming the interior walls of each of said drums, and having circumferential grooves and pockets located at spaced intervals apart in the bottom of said grooves. 110

4. In mineral classifying and concentrating apparatus, a rotatable trommel comprising a series of cylindrical spaced drums arranged concentrically to a common axis, a series of cylindrical drums arranged alternately between the drums of the first men- 115

120

125

130

- tioned series, the drums of the first series being of different diameter to the drums of the second series, and riffle plates forming the interior walls of each of said drums, and 35
- 5 having circumferential grooves, and pockets in said grooves each formed with substantially square upstanding faces.
5. In mineral classifying and concentrating apparatus, a rotatable trommel, comprising 40 a series of cylindrical spaced drums, riffle plates forming the interior walls of each of said drums, circumferential grooves in said riffle plates, and pockets located at spaced intervals apart in the base of each of 45 said grooves, each of said pockets having at least one of its upstanding edges formed substantially square. 50
6. In mineral classifying and concentrating apparatus, a rotatable trommel having 55 the interior wall thereof formed of riffle plates provided with circumferential grooves, and pockets in the base of each of said grooves said pockets having a substantially square upstanding rear edge and an inclined leading edge. 60
7. In mineral classifying and concentrating apparatus, a rotatable trommel, comprising a series of cylindrical drums arranged at spaced intervals apart and concentrically 65 with relation to the axis of said trommel, a second series of cylindrical drums located at spaced intervals apart and each disposed alternately with the drums of the first series, the drums of the second series being located eccentrically of the axis of the trommel and each successively angularly displaced with reference to the adjacent trommel of the same series. 70
8. In mineral classifying and concentrating apparatus, a rotatable trommel comprising 75 a series of cylindrical drums arranged at spaced intervals apart, and concentric with the axis of said trommel, a series of eccentric ring divisions between each of said drums and each connected end to end with adjacent drums, riffle plates forming a lining for said drums and pockets located at spaced intervals circumferentially, each of said pockets being formed with an inclined leading edge and a substantially square upstanding rear edge. 80
9. In mineral classifying and concentrating apparatus, a rotatable trommel comprising 85 a series of cylindrical drums connected end to end and extending the whole length of the trommel each alternate drum being disposed concentrically with the axis of said trommel, and each drum between said concentrically disposed drums being angularly located eccentrically of the axis of the trommel, the eccentrically located drums being successively displaced angularly throughout the length of the trommel, cylindrically curved riffle plates forming a lining for the interior of each of said drums, and pockets 90 located at spaced intervals circumferentially in each of said plates. 95

WILLIAM WHITEHEAD RICHARDSON.
